UNITED STATES PATENT OFFICE.

ARTHUR C. VAN HOUWELING, OF PELLA, IOWA.

ATTACHMENT FOR LATERAL CONVEYERS.

1,080,940.

Specification of Letters Patent.

Patented Dec. 9, 1913.

Application filed February 10, 1913. Serial No. 747,572.

To all whom it may concern:

Be it known that I, ARTHUR C. VAN HOUWELING, a citizen of the United States, and resident of Pella, in the county of Marion 5 and State of Iowa, have invented a certain new and useful Attachment for Lateral Conveyers, of which the following is a specification.

The object of my invention is to provide 10 an attachment for lateral conveyers of simple, durable and inexpensive construction, having parts so made and arranged that in one position of the attachment a lateral conveyer may swing in a horizontal plane while 15 in another position of said attachment the conveyer may be locked against horizontal swinging movement.

My invention consists in certain details, 20 in the construction, combination and arrangement of the various parts of the device whereby the objects contemplated are attained, as hereinafter more fully set forth, pointed out in my claims and illustrated in the accompanying drawings, in which—

25 Figure 1 shows a side elevation of a part of a threshing machine and lateral conveyer provided with an attachment, embodying my invention. Fig. 2 shows a detail view of a portion of the mechanism for locking 30 the conveyer against swinging movement in a horizontal plane. Fig. 3 shows a detail, sectional view taken on the line 3—3 of Fig. 2. Fig. 4 shows a detail view of the mechanism shown in Fig. 2 taken at right 35 angles to the view in Fig. 2, and Fig. 5 shows a detail view of the ratchet wheel which forms a part of my device.

In the accompanying drawings, I have used the reference numeral 10 to indicate 40 that portion of the threshing machine shown. Suitably mounted on the main body of the threshing machine is a frame 11 of a band cutter and feeder which may be of ordinary construction. I preferably mount 45 on my machine two lateral conveyers 12 which may be mounted in the manner and by the means described in my application for patent on a lateral conveyer for threshing machines, Serial Number 624,297, filed 50 on May 1, 1911. I preferably employ mechanism 13 also described in my said prior application for elevating and lowering each lateral conveyer. For firmly supporting the 55 lateral conveyer frames against movement in a horizontal plane, when desired, and for permitting said movement, when desired,

I have provided the following means which may be secured or released by an operator either at the outer end of the side conveyer or upon the ground near the pivoted end 60 of said conveyer. A similar device is used for each lateral conveyer and I will describe the device therefore fully as applied to one of said conveyers.

Extending laterally from the frame of 65 one of the conveyers 12 is a bracket 14 to which is pivotally connected a rod or tube 15. I provide on the frame of the band cutter a laterally extending bracket 16, shown in Fig. 1. Pivots secured thereto is a rod 70 17. Detachably mounted on the end of the tube or rod 15 is a hollow clutch or tube 18. The walls of the clutch 18 are slotted at 19. On one side of the clutch 18, adjacent to the slot 19 I provide parallel 75 opposite disk shaped lugs 20 and 21. One end of the rod 17 is received in the clutch 18, as shown in Figs. 2, 3 and 4. It is obvious that so long as the rod 17 may slide freely in the clutch 18, the lateral conveyer 80 12 may swing freely in a horizontal plane and that when said rod 17 and said clutch 18 are locked against movement relative to each other, then the lateral movements of the conveyer 12 will be prevented. 85

Extended through the disks 20 and 21 is a bolt 22 having rotatably mounted thereon a ratchet wheel 23. This ratchet wheel 23 is provided on its side adjacent to the lug 20 with a plurality of spaced lugs 24 illustrated in Figs. 4 and 5. The surface of the bolt or lug 20 adjacent to the ratchet wheel 23 is provided with a plurality of notches or depressions 25 designed to receive and coact with the lugs 24 in certain positions of the 90 movement of the ratchet wheel 23 with relation to said lug 20. Pivoted to one arm of the lever 26 is 95 a swinging pawl 27 designed to be received in the notches 28 of the ratchet wheel 23 to thereby operate said wheel. A contractile coil spring 29 is secured to the pawl 27 and is detachably secured at its other end to a 100 support 30 on the tube 15 as shown in Figs. 2 and 4. Ropes 31 and 32 are secured to the opposite ends of the lever 26. The rope 32 is extended over a pulley 33 to be accessible to an operator standing on the 105 ground near the bandcutter and feeder and the rope 31 is extended along the conveyer 110

frame to a point near the outer end thereof where it is accessible to an operator at the delivery end of the conveyer. Upon the clutch 18 is a projecting guard member 34. 5 When either of the ropes 31 or 32 are pulled, the pawl 27 engages one of the ratchet teeth, thereby moving the ratchet wheel one tooth space. The movement of the lever 26 each time is limited by the guard device 34. 10 It will be understood that the clutch 18 and the disk shaped lugs 20 and 21 are of somewhat resilient material. When the lugs 24 are received in the notches 25, the resiliency of the members 20 and 21 causes them 15 to stand at the limit of their movement away from each other. Assuming that at the beginning of the operation of the device the lugs 24 are received within the notches 25 and that either of the ropes 31 or 32 are 20 pulled, then the ratchet wheel will move one tooth space until the lever is stopped by the guard device 34 and the lugs 24 will be pulled out of the notches 25 and will engage the outer surface of the lug 20, thereby 25 pressing the lugs 20 and 21 together and frictionally gripping and holding the rod 17 in the clutch 18. As long as the lugs 24 are received in the notches 25, the rod 17 will slide freely in the clutch 18 and the lateral conveyer may be swung in a horizontal plane, as desired. When the conveyer has reached 30 the upper position, the operator, by pulling upon either of the ropes may move the ratchet wheel until the lugs 24 are drawn out 35 of the notches 25 and the device will be locked or clamped.

My device for controlling the horizontal

swinging movement of the lateral conveyer is simple and of durable and inexpensive construction. It is easily operated from the 40 stack which is being built or by an operator standing on the ground near the band cutter and feeder.

I claim as my invention:

1. In a device of the class described, the 45 combination of a main frame, a conveyer frame pivoted thereto to swing in a horizontal plane, two rods slidably connected with each other, one being attached to the main frame and the other being attached to the 50 conveyer frame, and means for gripping said rods together to prevent lateral movements of the conveyer frame and for releasing said rods so that one may freely slide within the other, and the conveyer frame 55 may be freely moved laterally.

2. In a device of the class described, the combination of a main frame, a conveyer frame pivoted thereto to swing in a horizontal plane, two rods slidably connected with 60 each other, one being attached to a main frame at a point spaced apart from the pivotal point of the conveyer frame, the other being attached to the conveyer frame, means for securing said rods together against sliding movement with relation to each other and means for operating said first means 65 from either end of the conveyer.

Des Moines, Iowa, January 30, 1913.

ARTHUR C. VAN HOUWELING.
